UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER, ENGLAND.

PERCUSSIVE FIRING MECHANISM OF BREECH-LOADING GUNS.

1,105,625.

Specification of Letters Patent.

Patented Aug. 4, 1914.

Application filed October 18, 1913. Serial No. 795,854.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Percussive Firing Mechanism of Breech-Loading Guns, of which the following is a specification.

This invention relates to percussive firing mechanism for breech loading guns, of the kind in which the striker is released by a trigger or firing handle mounted on the gun carriage.

The chief object of the present invention is to provide improved means whereby the trigger or firing handle can be mounted on a part of the carriage which is not co-axial with the gun trunnions, and the operative relationship between the said trigger or handle and the striker can be maintained notwithstanding the movements of the gun in elevation or depression.

According to this invention the gun cradle is provided with a pivoted device suitably connected with the firing shaft and having a curved surface with which the trigger or firing handle, or a part moved thereby, is capable of engaging at any elevation of the gun to transmit movement to the firing shaft and thereby fire the gun.

In order that the said invention may be clearly understood and readily carried into effect, we will describe the same more fully with reference to the accompanying drawings, in which:—

Figure 1 is a side elevation of a portion of a gun mounting provided with a constructional form of the improved firing mechanism, the gun being in its horizontal position. Fig. 2 is a plan of a portion of Fig. 1, and Fig. 3 is a view similar to Fig. 1 showing the gun elevated to an angle of about 70 degrees. Fig. 4 is a view similar to Fig. 1 showing a slightly modified form of the mechanism. Figs. 5, 6 and 7 are respectively a side elevation, a partial sectional plan, and a rear elevation showing a constructional form of the invention in which the trigger is carried on the handle of the elevating hand wheel or lever. Figs. 8 and 9 are respectively a side elevation and

a sectional plan showing a further application of the improved firing mechanism.

A is the gun, B the gun cradle, B' one of the trunnions and C the gun carriage.

D represents the aforesaid device which is pivoted at d to the cradle. D' is the trigger or firing handle and D² the firing shaft.

E is the elevating handwheel or lever which is omitted from Figs. 5 and 8.

In the examples shown, the aforesaid device D is in the form of a curved plate the pivot d of which is arranged parallel to the trunnions and in front thereof when the gun is horizontal. The firing handle D' is in Figs. 1 to 4 pivoted at d' on the carriage C, preferably (as shown) at a point behind the trunnions. A roller d'' carried by an arm of the said handle bears against either the front or, as illustrated, the rear surfaces of the said curved plate D. The curvature of the plate when the latter is in its normal position is concentric with the trunnions. The curved plate may be connected either directly as in Figs. 1 to 3 or through a two armed lever as in Fig. 4 to a connecting rod D² (constituting the aforesaid firing shaft) carried on a guard plate attached to the cradle, the rear end of this rod being pivoted to a link d² which lies in loose contact with an arm D^x on the gun; this arm is suitably connected with the sear of the striker. The rod D² has a spring D^{2x} which serves to hold the plate D in contact with the roller d''. The said curved plate is shown in Figs. 1 to 4 as being for convenience of construction in the form of a ring or disk, and the firing handle is disposed in a convenient position contiguous to the elevating hand wheel E.

The aforesaid pivoted device having a curved surface, instead of being in the form of a curved plate, ring or disk as aforesaid, may be modified in shape in order to adapt it to the requirements of the particular form of mounting with which it is to be employed.

In the construction shown in Figs. 5 to 7 the firing trigger D' is carried on the handle of the elevating handwheel or lever E which is mounted on the gun carriage. The said trigger operates through the known arrangement of a sliding pin d³, a lever d^{3x} and another sliding pin d⁴ upon an arm d^{4x} on a

vertical shaft d^5 mounted on the carriage. This shaft has another arm d^{5x} that carries the aforesaid roller d'^x . The rod D^2 connected to the curved plate D operates upon 5 the arm D^x on the gun in a similar manner to that described with reference to Figs. 1 to 3.

In the construction shown in Figs. 8 and 9, the rod D^2 is connected at its rear end to 10 an arm D^3 which carries a bevel pinion D^{3x} gearing with a similar pinion forming part of or connected to a sleeve D^{4x} . This sleeve is mounted on the cradle and carries a 15 plunger D^5 which is adapted to engage with a sleeve D^{5x} carried by the gun, in a similar manner to that described in the prior British specification No. 16216 of 1911. In the example shown in Figs. 8 and 9 the rod D^2 is displaced from the trigger D' on the elevating handwheel or lever in a similar manner to that described with reference to Figs. 20 5 to 7.

The curved plate D in the constructions of Figs. 5 to 9 differs slightly from that of 25 Figs. 1 to 4 in that it is not a complete ring.

What we claim and desire to secure by Letters Patent of the United States is:—

1. In percussive firing mechanism for 30 ordnance, the combination with a non-elevating part of the mounting and the gun cradle, of a firing device mounted on said non-elevating part, a curved member moved by said device and pivotally mounted on the cradle in co-axial relation with the gun 35 trunnions, a striker releasing member on the gun, and a connecting rod pivoted to said curved member and serving to transmit the pivotal movements of said curved member to the striker releasing member on 40 the gun.

2. In percussive firing mechanism for 45 ordnance, the combination with a non-elevating part of the mounting and the gun cradle, of a firing device mounted on said non-elevating part, a curved member moved by said device, a pivot for said member carried by the cradle and arranged parallel to the gun trunnions, a striker releasing member on the gun and a connecting rod pivoted

to said curved member and serving to transmit the pivotal movements of said curved member to the striker releasing member on the gun. 50

3. In percussive firing mechanism for 55 ordnance, the combination with a non-elevating part of the mounting and the gun cradle, of a firing device mounted on said non-elevating part, a curved plate moved by said device, a pivot for said plate carried by the cradle and arranged parallel to the gun trunnions, a striker releasing member on the gun and a connecting rod pivoted to 60 said curved plate and serving to transmit the pivotal movements of said curved plate to the striker releasing member on the gun. 65

4. In percussive firing mechanism for 70 ordnance, the combination with a non-elevating part of the mounting and the gun cradle, of a firing device mounted on said non-elevating part, a curved plate moved by 75 said device, a pivot for said plate carried by the cradle and arranged parallel to the gun trunnions, a striker releasing arm on the gun, a lever in contact with said arm and a connecting rod pivoted to said lever and to the curved plate.

5. In percussive firing mechanism for 80 ordnance, the combination with a non-elevating part of the mounting and the gun cradle, of a firing device mounted on said non-elevating part, a curved plate moved by 85 said device, a pivot for said plate carried by the cradle and arranged parallel to the gun trunnions, a striker releasing arm on the gun, a lever in contact with said arm, a connecting rod pivoted to said lever and to the curved plate, and a guard plate carried by the cradle and covering said means, the lever and the arm, said lever being pivoted to said guard plate. 90

In testimony whereof we affix our signatures in presence of two witnesses.

ARTHUR TREVOR DAWSON.
GEORGE THOMAS BUCKHAM.
